UNITED STATES PATENT OFFICE.

DOROTHY HOOPER, OF NAHANT, MASSACHUSETTS.

LIFE-SAVING RAFT.

1,269,445.

Specification of Letters Patent. Patented June 11, 1918.

Application filed October 29, 1917. Serial No. 198,930.

To all whom it may concern:

Be it known that I, DOROTHY HOOPER, a subject of the King of Great Britain, residing at Nahant, in the county of Essex and State of Massachusetts, have invented new and useful Improvements in Life-Saving Rafts, of which the following is a specification.

This invention relates to life saving rafts and the object in view is to provide a raft having an inflatable body, preferably constructed to provide a number of independent airtight compartments thereby insuring the buoyancy and load carrying capacity of the raft even when pierced by shells, projectiles or other objects.

A further object of the invention is to produce a life saving raft which may be compactly stowed away, preferably on the deck of a vessel, enabling a large number of such rafts to be piled one upon another. The rafts may be quickly inflated and thrown overboard in case there is not time to lower the boats.

One of the principal objects of the invention is to produce a raft of the character referred to which may be used either side up, equipment of the raft comprising a guard rail or fence which may be applied to the raft regardless to which side is up when the raft is thrown into the water; also oar locks which may be applied to either side of the raft, and a rudder which may be inverted while the raft is in the water.

With the above and other objects in view, the invention consists in the novel construction, combination and arrangement of parts, herein described, illustrated and claimed.

In the accompanying drawings:—

Figure 1 is a plan view of the life saving raft.

Fig. 2 is a side elevation thereof.

Fig. 3 is a fragmentary horizontal section showing the manner of constructing and holding one of the stanchion sockets.

Fig. 4 is a fragmentary view showing the invertible rudder and the holding means therefor.

Fig. 5 is a fragmentary vertical transverse section showing the holding means for one of the paddles.

The life saving raft contemplated in this invention is preferably made somewhat in the shape of a boat having a pointed bow and a rounded stern as shown. The boat

comprises a body 1 which is in the form of an inflatable bag or sack of rubber or other material which is impervious to air and which will remain inflated for an indefinite period of time. The interior of the bag or sack is divided by means of flexible partitions 2 composed of rubber or other airtight material or fabric into independent air-tight compartments 3, each being equipped with an inflating valve 4.

Extending around the forward portion of the body is a band 5 of cork or other buoyant material, the same being stitched, riveted or otherwise fastened to the body 1. It is also preferred to form the stern of the section 6 of the body, of cork and at the extreme rear of the stern section 6, I place a rudder 7 having a rudder post 8 which extends through an opening 9 formed partly in fixed bearing plate 10 riveted or otherwise secured to the stern 6, and hinged or displaceable plates or keepers 11 which may be folded back to allow the rudder post 9 to be removed in order that the rudder may be inverted, or the rudder post turned end for end. This enables the rudder to be properly set after the raft has been thrown overboard, in case the raft should land in the water wrong side up.

Extending along the opposite sides of the raft are reinforcing strips 12 of heavy canvas or other strong flexible material and secured to said strips 12 are stanchion sockets 13 open at top and bottom. The sockets 13 are securely fastened to the bands 12 and each socket is adapted to receive one of a series of stanchions 14, the stanchions being connected by a flexible net 15 forming a fence designed to extend entirely around the body 1 for the protection of the occupants of the raft, to prevent them from being washed off the raft when there is a heavy sea running. Each stanchion 14 is formed with a stop shoulder or collar 16 which when the stanchion is in place, abuts against the upper end of the socket 13. A pin 17 is attached to each stanchion 14 by means of a flexible connection 18 such as a chain and when the stanchion is in place, the pin 17 is inserted through holes 19 in the socket and also through a hole 20 in the stanchion. This prevents the stanchion from getting loose.

Strips 21 preferably of flexible material such as canvas, are stitched or otherwise

secured to the strips 12 and are designed to receive and hold a plurality of paddles 22 which are thus accessible to persons on the raft irrespective of which side is up. 5 Launching rings or eyes 23 are permanently fastened to the sides of the raft for the purpose of enabling the raft to be raised and lowered by ropes or other tackle.

From the foregoing description taken in connection with the accompanying drawings it will now be seen that I have produced a life saving raft which is light in weight, which may be compactly stored, enabling a large number of such rafts to be piled one upon another in compact order, requiring a minimum amount of space. The raft may be quickly inflated and when so inflated and thrown into the water, it will support a large number of persons. It will of course be understood that the raft may be made in any size desired. When used on transports, it will be made of considerable size so as to accommodate a great number of soldiers. By reason of the construction described and shown, the raft may be thrown overboard in an emergency where there is no time to lower the usual life boats. Irrespective of which side of the raft is up when it strikes the water, the guard rail or fence, 20 and the rudder may be adjusted, and paddles are accessible. The fence or guard, by reason of the flexibility thereof, may be rolled up in a bundle and lashed to the side of the mattress and may be readily set in position 25 in a short time. The cork stern and the cork band extending around the bow of the raft increase the buoyancy thereof and insure the same floating in case the raft should be thrown overboard before being inflated. It 30 will be obvious that the raft cannot be dashed to pieces in a heavy sea by coming in forcible contact with the hull of a vessel as the construction of the raft is flexible throughout. 35

40 In danger zones in time of war, one or more rafts may be kept in an inflated condition ready for immediate use. The rafts may be inflated while still piled one upon another. Where the rafts are formed with more than one airtight compartment, a corresponding number of inflating pumps may 45 be supplied with each raft so that in case of necessity a number of persons may handle

the air pumps and quickly inflate all compartments of the raft. 55

One or more pumps 24 may be mounted upon the raft and flexible connections 25 may lead to the intake valves 26 connected with each of the air compartments of the raft. This will expedite the inflation of all 60 of the air compartments.

I claim:—

1. A life saving raft comprising a flexible and inflatable body, a flexible guard rail extending around said body and comprising a 65 series of stanchions, and tubular sockets for said stanchions extending transversely of the marginal portion of the body, said sockets being open at both ends.

2. A life saving raft comprising a flexible 70 and inflatable body, a flexible guard rail extending around said body and comprising a series of stanchions, and tubular sockets for said stanchions extending transversely of the marginal portion of the body, said sockets 75 being open at both ends, each of said stanchions being formed with a stop shoulder adapted to rest against the upper extremity of the respective socket.

3. A life saving raft comprising a flexible 80 and inflatable body, a flexible guard rail extending around said body and comprising a series of stanchions, tubular sockets for said stanchions extending transversely of the marginal portion of the body, said sockets 85 being open at both ends, and a pin secured by a flexible connection to each stanchion and adapted to be inserted through holes in each socket and stanchion for locking the stanchions in place. 90

4. A life saving raft comprising a flexible and inflatable body, an invertible rudder, and bearing means for the post of said rudder, said bearing means comprising a fixed plate and a displaceable plate, said plates 95 being formed in their meeting edges with a bearing opening for the rudder post.

5. A life saving raft comprising a flexible and inflatable body, a band of cork extending around the bow of the raft, and an after 100 deck or stern portion comprising a cork section flexibly connected to the main body of the raft.

In testimony whereof I affix my signature.

DOROTHY HOOPER.
